FIG. III

ALEX ANDERSON INVENTOR.

BY
Stanley M. Udal
ATTY VEY

UNITED STATES PATENT OFFICE.

ALEXANDER ANDERSON, OF DETROIT, MICHIGAN, ASSIGNOR TO EARL HOLLEY, OF DETROIT, MICHIGAN.

AUTOMATIC EJECTION DEVICE FOR DIE-CASTING MACHINES.

Application filed February 5, 1923. Serial No. 617,042.

To all whom it may concern:

Be it known that I, ALEXANDER ANDERSON, a citizen of the United States, residing at 9299 Cascade Ave., Detroit, in the county of Wayne and State of Michigan, have invented certain new and useful Improvements in Automatic Ejection Devices for Die-Casting Machines, of which the following is a specification.

10 This invention relates to automatic ejection devices for die-casting machines of the type described in the patent application Serial No. 504,988, applied for by D. W. Candler, October 3, 1921. This application discloses an ejection device adapted to be used with a rotating molding machine, but it is also particularly adapted to be used with stationary molding devices.

Figure I shows a sectional elevation on the plane X—Y of Figure II.

Figure II shows a plan view showing the ejectors in the position they assume after the castings have been ejected, the broken line showing the position the mechanism is in when the castings are being ejected.

Figure III shows in elevation the end view of the ejection device.

In these figures 26 represents a rotating table upon which the whole device is arranged and 27 the stationary base upon which 26 revolves. 1 is the radially moveable inner mold and 2 is the stationary outer mold. 3 is the support and slide for the inner mold 1. 4 is the radially stationary support for the outer mold 2, radially locked to the rotating table 26 by means of the bolt 29. (Fig. I) 6 6 6 are the knock-out pins for the radially stationary outer mold 2. 7 is the slide which carries the knock-outs 5 5 5. 40 8 is the slide which moves the knock-outs 6 6 6. 9 is the lever which moves the slide 7.

10 is the pin connecting the lever 9 to the slide 7, the lever being slotted so as to allow the slide 7 to move freely. This pin is provided with a nut so that it may be locked in place. 11 is the fulcrum for the lever 9 which consists of a bolt mounted on the mold support 4. 12 is a projecting arm integral with the lever 9. 13 is a stationary roller supported from the stationary base 27 by means of the projecting bracket 28. The purpose of this roller 13 will be described later.

25 is an adjustable stop limiting the movement of the slide 7 with reference to the stationary support 4 of the mold 2. 14 is a pin in the extreme end of the lever 9. 15 is an adjustable shackle connecting this pin with 16 which is a turnbuckle connecting the 60 shackle 15 with the rod 17. The rod 17 is integral with the square piece 19 and is provided with double lock-nuts 18 which serve as a stop. This piece 19 is squared so that it can slide in a slot in the projection 30 which supports the mold 1. This piece 19 is provided with a notch 20 which engages with a corresponding projection 21 integral with the support 3. 22 is a bevel face at the extreme end of 19. 23 is a corresponding stationary projection which is integral with the base 26 of the molding machine. 24 is a spring pressed plunger which presses the piece 19 into the guide in the slotted projection 30, causing 19 to engage with the projection 21 by means of the notch 20.

Operation: The knock-out pins in the moveable mold 1 are operated by a cam not shown in a manner similar to that described in the patent application of Candler referred to above. The novelty in this invention resides in the operation of the knock-outs 5 5 5 in unison with the motion of the mold 1 and its support 3.

When the mold 1 is moved in so as to touch the mold 2 the support 3 and projection 30 engages with the lock-nuts 18 and carries the rod 17, lever 9 and slide 7 backwards so as to cause the slide 7 to contact with the stop 25, thus carrying the knock-outs 5 5 5 back into position for pouring, the stop 25 merely prevents inertia from carrying the slide past the position for pouring. When the mold opens, at first the piece 19 is stationary and is then carried back with the mold 1 and its support 3 because the projection 21 engages with the notch 20 on the piece 19. There must be a dwell, however, between the initial opening of the mold and the motion of the knock-out pins 5 5 5 because the molds are opened whilst the metal in the mold is still red hot and the pins would enter the molten metal unless this clearance was provided so that there are a few seconds interval between the opening of the molds and the motion of the knock-out pins 5 5 5.

The knock-out pins 5 5 5 are thereupon

carried inwards (radially) as the mold opens so the knock-outs 5 5 5 move inwards relatively to the mold 2. After the casting has been ejected by this means the mold 1 continues to travel back and the piece 19 contacts on its bevel face 22 with the stationary projection 23. This causes the spring 24 to be compressed and thereby allowing the piece 19 to move over to the left (on Figure II), 10 the notch 20 thereby disengaging itself from the projection 21.

The piece 19 is now free from the mold support 3, although supported in the guide 30, hence when the stationary roller 3 strikes 15 the arm 12 the lever 9 is rotated about its stationary pin 11 and the slide 7 is moved to the right. The knock-outs 5 5 5 and the lever 9 assume the position shown on Figure II in full lines, being carried back by reason 20 of the resulting motion of the slide 7. The stop 25 prevents the knock-outs overrunning the position determined by the location of the roller 13 as they would tend to do under the influence of the inertia of the moving 25 masses 7 and 5. The knock-outs are thus withdrawn and it is thus possible to insert a core in the mold if a core is needed in the particular mold used.

When the molds are closed the projection 30 of the support 3 of the mold 1 again contacts with the lock-nuts 18. This merely makes sure that the slide 7 is contacting with the stop 25. This precaution is necessary as if by accident the knock-outs were 35 left projecting even slightly into the mold they would be welded into the casting because of their small size and the rapidity in which they would be heated up were they allowed to project into the path of the 40 molten iron.

What I claim is:

1. In a molding machine having matching molds consisting of a stationary mold and a moveable mold, knock-out pins in the stationary mold, a slide upon which said knock-out pins are mounted, a lever pivotally connected to said slide, a stationary fulcrum for said lever, and a link connecting said lever to the moveable mold whereby as the molds 45 are opened the knock-out pins are operated.

2. In a molding machine having matching molds consisting of a stationary mold and a moveable mold, knock-out pins in the stationary mold, a slide upon which said knock-out pins are mounted, a lever pivotally connected to said slide, a stationary fulcrum for said lever, a notched link adapted to connect said lever to the said moveable mold, a beveled surface at the end of said link, a corresponding stationary beveled surface adapted 50 to contact with the beveled surface on the end of said link whereby as the moveable mold is opened the connecting link is first

moved with the moveable mold and is later disengaged from said moveable mold. 65

3. In a rotating molding machine having matching molds consisting of a radially stationary mold and a radially moveable mold, knock-out pins in the stationary mold, a slide upon which said knock-out pins are mounted, a lever pivotally connected to said slide, a stationary fulcrum and a projecting arm for said lever, a link connecting said lever to the said moveable mold, means for disengaging said link from said moveable mold, a stationary roller adapted to contact with said projecting arm of said lever whereby the knock-out pins are returned to their original position during the rotation 70 of said molding machine. 75

4. In a molding machine having matching molds consisting of a stationary mold and a moveable mold, knock-out pins in the stationary mold, a slide upon which said knock-out pins are mounted, a lever pivotally connected to said slide, a stationary fulcrum for said lever, a link connecting said lever to the said moveable mold, an adjustable stop on said lever adapted to engage with said moveable mold, an adjustable stop on said slide 80 for limiting the motion of said slide relative to said stationary mold. 85

5. In a molding machine having matching molds consisting of a stationary mold and a moveable mold, knock-out pins in the stationary mold, a slide upon which said knock-out pins are mounted, a lever pivotally connected to said slide, a stationary fulcrum for said lever, a link connecting said lever to the said moveable mold, a notch on said link 95 adapted to engage with said moveable mold after said moveable mold has moved a predetermined distance, an adjustable stop on said link adapted to engage with said moveable mold when said mold is moved to the 100 closed position whereby said knock-out pins are returned to their original position when the moveable mold is moved to its closed position. 105

6. In a molding machine having matching molds consisting of a stationary mold and a moveable mold, knock-out pins in the stationary mold, a slide upon which said knock-out pins are mounted, a lever pivotally connected to said slide, a stationary fulcrum 110 for said lever, a link connecting said lever to the said moveable mold, a notch on said link adapted to engage with said moveable mold after said moveable mold has moved 115 a predetermined distance, means for returning said knock-out pins to their original position when the moveable mold is moved to its closed position. 120

In testimony whereof I affix my signature.

ALEX ANDERSON.
